UNITED STATES PATENT OFFICE.

ANDREA PASQUALE SACCO, OF GENOA, ITALY.

VACUUM TANK.

Application filed July 28, 1924. Serial No. 728,747.

To all whom it may concern:

Be it known that I, ANDREA PASQUALE SACCO, a subject of the King of Italy, residing at Genoa, Italy, have invented a new and useful Vacuum Tank, of which the following is a specification.

This invention relates to improvements in vacuum tanks of the type in which a float is employed to control the admission of air and the application of suction to the tank, and the discharge of fuel from the tank.

One of the objects of the invention is to provide a rotary disk valve in the line of communication between the engine and the vacuum tank, and improved means for operating this valve with a snap or jerk so that the valve will be instantaneously opened or closed.

A further object of the invention is to provide an air admission valve also controlled by the last mentioned means, said means in turn being under the control of the usual float.

Another object of the invention is to provide a novel valve for controlling the discharge of fuel from the inner to the outer chamber of the vacuum tank.

With the foregoing objects outlined and with other objects in view which will appear as the description proceeds, the invention consists in the novel features herein-after described in detail, illustrated in the accompanying drawings, and more particularly pointed out in the appended claims.

Referring to the drawings:

Figure 1 is a vertical diametrical sectional view of the improved vacuum tank.

Fig. 2 is a similar view of the upper portion of the tank taken at right angles to Fig. 1 and with parts broken away.

Fig. 3 is a bottom plan view of a portion of the inner vessel.

Fig. 4 is a top plan view of the tank.

In the drawings, 1 is the usual outer receptacle containing an inner receptacle 2. These receptacles are connected at their upper ends by a ring 3 and screws 3^a. One of these screws, as best shown in Figs. 2 and 4, has a hole 3^b through the same to admit air constantly into the outer chamber 1. A cap 4 is arranged at the upper ends of the chambers 1 and 2 and carries an intake connection 5 which is adapted to be connected to the fuel supply tank, and a suction connection 6 adapted to be connected to the intake manifold of the engine. The

lower portion of the receptacle 1 is adapted to be connected to the carburetor of the engine and a valve 7 is provided at this point for regulating the feed of fuel to the carburetor.

A rectangular casing 8 is arranged in the lower portion of the chamber 2 and has apertures 8^a to permit the fuel to flow from the inner chamber to the outer chamber. Two pivotally mounted valves 9 cooperate with these apertures and these valves are carried by a double-armed lever 10 pivotally mounted on a vertical shaft 11. It will be noted that one arm of the lever 10 is shorter than the other so that the two valves will have different displacements during operation, the valve of the short arm having a very small movement and the valve of the long arm a relatively greater movement. Such an arrangement has for its object to cause the valve of the short arm, on the suction phase, to be instantaneously drawn to its seat and to transmit the movement to the valve on the long arm, to provide sensitivity and instantaneous closure of the apertures 8^a, while during the delivery phase, the valve on the long arm, being at a greater distance from its seat than the other valve, will allow the passage of larger quantities of fluid. The short arm of the lever carries a projection 10^a adapted to abut against one side of the casing and thereby form a stop so that the valves will not open too far. A cross bar 8^c extends across the lower open end of the casing and supports the lower end of the shaft 11.

A vertical pin 12 extends upwardly from the casing 8 and acts as a guide for a sleeve 13 which carries at its upper end a vertical pin 14 secured to the tube 13 by a pin 15, the ends of which project beyond diametrically opposite sides of the tube. A float 16 is slidably mounted on the tube and is adapted in rising to strike the projecting ends of the pin 15 for raising the rod 14, while the float in descending will strike a flange 17 at the lower end of the tube for lowering the pin 14.

As best shown in Figures 1 and 2, the suction connection 16 leads into a box 18 arranged within the chamber 2. This box is provided in one of its walls with a circular series of apertures which are adapted to register during the suction phase with apertures 20 arranged in a circular series in the disk valve 21, which latter is rotatably

mounted on the box 18. It is obvious that when the valve is turned to cause the apertures 20 to move out of register with the apertures of the box 18, the application of engine suction will be cut off. The valve 21 is provided with projecting arms 23 adapted to be struck by a pin 22 fixed on and projecting from the pin 14. A bearing block 24 is fixed to the cap 4 and pivotally 10 supports levers 25 carrying counterweights 26. The intermediate portions of these levers are pivotally connected to the outer ends of links 27 which have their opposite ends pivotally connected to a block 28 fixed on the pin 14. The pin 14 is provided at its upper end with a head 29 which moves in a stationary tube 30 and is adapted to displace a ball valve 31, arranged in the tube 30 and adapted to control the admission of 15 outside air to the inner chamber 2.

In operation, the float valve 16 will descend and strike the flange 17 so that the links 27 will be pulled downwardly with a jerk and the head 29 will release the ball 25 valve 31 and permit the same to close. Immediately after this the pin 22 will strike the lower one of the arms 23 and swing the valve 20 so that the openings in this valve communicate with the openings in the box 30 18. At this time, it is obvious, that the chamber 2 will be closed to atmosphere and that engine suction will be applied to the chamber 2. This suction will snap the valves 9 into closed position, and then the 35 suction will be created in the connection 5 so that fuel will be drawn from the main supply tank into the chamber 2. This action will continue until the float 16 rises sufficiently to strike the pin 15 and move the block 28 upwardly until the links 27 move slightly beyond a horizontal position, at which time, the counterweights 26 will fall and cause the pin 14 to move up with a snap, and the arm 22 will strike the upper arm 23 and again close the valve 21. Immediately after the valve 21 is closed the pin 14 will rise sufficiently to cause the head 29 to unseat the valve 31, so that outside air 40 will again be admitted to the chamber 2. At this time the valves 9 will open under the influence of the pressure exerted by the fuel in the chamber 2 and the fuel will 45 flow from chamber 2 into chamber 1.

From the foregoing it is believed that the construction, operation and advantages 55 of the invention may be readily understood, and it is apparent that changes may be made in the details disclosed without departing from the spirit of the invention as expressed in the claims. 60

What I claim and desire to secure by Letters-Patent is:

1. A vacuum tank including a normally closed chamber having a fuel inlet, a fuel outlet, an air inlet and a connection to apply suction to the interior of the chamber, a float arranged in the chamber, a valve for controlling the suction connection, pivotally mounted levers arranged in the chamber, counterweights supported by said levers, a rod on which the float is slidably mounted, links pivotally connecting the rod to said levers and adapted to be moved by the rod to both sides of a line drawn through the points at which the links are 75 pivotally connected to said levers so that the counterweights may move the rod with a jerk immediately after the inner ends of the links pass to one side or the other of said line, means operatively connecting said rod with said valve to permit the rod to open and close the latter, spaced abutments on the rod to limit the movement of the float on the rod, and a valve for controlling the fuel outlet of the chamber. 80

2. A vacuum tank as claimed in claim 1 including a valve for controlling the air inlet of the chamber, and means actuated by said rod for controlling the last mentioned valve. 90

3. The combination with a vacuum tank having a valve controlled by a float, of pivotally connected links forming a parallelogram, a valve actuating member connected to a pair of said links, and counterweights 95 connected to the other pair of said links.

4. In a vacuum tank, an inner chamber having a fuel outlet including a plurality of apertures, a pivotally mounted double-armed lever, valves carried by the arms of the lever for closing said apertures, one of said arms being longer than the other as and for the purpose described. 100

In testimony whereof I have signed my name to this specification.

ANDREA PASQUALE SACCO.
